UNITED STATES PATENT OFFICE.

ADOLPH BLOCK, OF BUFFALO, NEW YORK.

DESIGN FOR A BRACELET.

52,465.

Specification for Design.

Patented Sept. 24, 1918.

Application filed June 27, 1918. Serial No. 242,301. Term of patent 7 years.

To all whom it may concern:

Be it known that I, ADOLPH BLOCK, a citizen of the United States, residing at Buffalo, in the county of Erie and State of New York, have invented a new, original, and ornamental Design for Bracelets, of which the following is a specification.

In the accompanying drawings:

Figure 1 is a perspective front view of a bracelet embodying the design.

Fig. 2 is a perspective rear view thereof.

The bracelet shown comprises a watch A, a locket or the like B, and a band C connecting the watch and locket.

I claim:

The ornamental design for a bracelet as shown and described.

ADOLPH BLOCK.
